UNITED STATES PATENT OFFICE

GOTTFRIED NIEBEL, OF NEW YORK, N. Y.

DESIGN FOR AN ELECTRIC BULB OR SIMILAR ARTICLE

Application filed May 10, 1930. Serial No. 35,586. Term of patent 14 years.

To all whom it may concern:

Be it known that I, GOTTFRIED NIEBEL, a citizen of the United States, and resident of 419 West 115th Street, in the city of New York, in the county of New York, and State of New York, have invented a certain new, original, and ornamental Design for an Electric Bulb or Similar Article, of which the following is a specification, reference being had to the accompanying drawing, forming part thereof.

The view is an elevation of an electric bulb

or similar article showing my new design. The opposite side of the bulb is substantially the same as the side shown.

I claim:

The ornamental design for an electric bulb or similar article substantially as shown and described.

Signed at New York, in the county of New York and State of New York this seventh day of May A. D. 1930.

GOTTFRIED NIEBEL.
